UNITED STATES PATENT OFFICE.

MAX EUGENE SCHWAB AND ALPHONSE WUISCHPARD, OF NEW YORK, N. Y., ASSIGNEES TO HAMILTON WATCH COMPANY, OF LANCASTER, PENNSYLVANIA, A CORPORATION OF PENNSYLVANIA.

DESIGN FOR A WATCHCASE.

Application filed July 16, 1928. Serial No. 27,505. Term of patent 3½ years.

To all whom it may concern:

Be it known that we, MAX E. SCHWAB and ALPHONSE WUISCHPARD, residents of New York, county of New York, State of New York, have invented a new, original, and ornamental Design for Watchcases, of which the following is a specification, reference being had to the accompanying drawings, forming a part thereof.

Fig. 1 is a plan view of a watch case showing our new design;

Fig. 2 is an edge view thereof.

We claim:

The ornamental design for a watchcase, as shown.

In testimony whereof we hereunto affix our names.

MAX EUGENE SCHWAB.
ALPHONSE WUISCHPARD.
